ADJUSTABLE ABUTMENT FOR PISTONS

Julius E. Rasoletti, Cleveland Heights, Ohio, assignor, by mesne assignments, to Rockwell Manufacturing Company, Pittsburgh, Pa., a corporation of Pennsylvania

Application February 25, 1948, Serial No. 10,751

11 Claims. (Cl. 121—38)

1

This invention relates to devices for regulating the stroke of a work performing member, and more particularly to adjustable abutment means for limiting the stroke of a piston at any desired point in a cylinder.

In the operation of a tool, such as a drill, it is often desirable that means be provided for limiting the movement of the tool toward its work. It is frequently necessary that the travel of the tool be varied, and that there be means for indicating the travel obtained. A reciprocating piston may be employed for moving the tool or some other member, and, in order that the desired movement may be obtained, adjustable means may be provided for regulating the piston stroke. For regulating the travel of a piston carrying a tool or any other work performing member, there may be provided an abutment member in the cylinder for engagement by the piston, and manually operated means may be provided for adjusting the position of the abutment as indicated by visible markings at the exterior of the cylinder.

An object of my invention is to provide improved means for limiting the travel of a piston. Another object is to provide an abutment in a cylinder for engagement by a piston, and having improved means for adjusting its position as indicated by markings at the exterior of the cylinder. Other objects will appear in the course of the following description.

In the accompanying drawing there is shown for purposes of illustration, one form which my invention may assume in practice.

In this drawing:

Fig. 1 is a view, partially in section, of a cylinder and piston having my improved adjustable abutment associated therewith.

Fig. 2 is an enlarged sectional view of the adjustable abutment shown in Fig. 1.

Fig. 3 is a cross sectional view taken on the plane of the line 3—3 of Fig. 2.

Fig. 4 is a side elevational view of the structure shown in Fig. 2.

Referring to the drawing it will be noted that there is shown a motor, generally designated 1, of the reciprocating piston type including a cylinder 2 having a bore 3 in which a piston portion 4 is reciprocably received. Formed integral with the cylinder is a flange 6 which is adapted to be secured to suitable means for supporting the motor in any desired position. Fitting within the forward portion of the cylinder bore is a sleeve shaped member 8 which slidably receives a reduced portion 9 of the piston, and attached to the forward end of the cylinder is an annular

2

member 10 into which the reduced portion 9 moves as the piston makes its forward stroke. Rotatably mounted upon a forwardly projecting flange portion 11 of the annular member is a cap 12 having an opening 14 in axial alignment with the cylinder bore 2, and a further reduced piston portion 15 extends forwardly from the portion 9 through the opening 14. Formed in the flange portion 11 of the annular member 10, as shown in Fig. 3, is an annular groove 16, and threaded into openings in the cap 12 are members 18 having portions 19 extending into the annular groove for holding the cap against movement longitudinally relative to the annular member. Arranged within the member 10 and having threaded engagement therewith is an annular abutment member 20 surrounding the piston portion 15 and adapted to be engaged by the forward end of the piston portion 9 for limiting the stroke of the piston in a forward direction.

In order that the abutment member may be moved to any desired position within the member 10 and then locked in such position, there is provided a pin 22 extending through an opening in the cap 12 and having a reduced threaded portion 23 which extends freely through an opening in a portion 24 of the abutment member and is threaded into an opening 25 in a portion 26 of the abutment member, the portions 24 and 26 being separated by a cut 28, as shown in Fig. 2. It will be seen that the pin 22 connects the cap 12 and the abutment member 20 for rotation together, and that rotation of the abutment member will result in its movement longitudinally relative to the member 10 by reason of the threaded engagement between them. As the abutment member moves longitudinally within the member 10, the pin 22 moves with it through the opening in the cap 12. In order that the operator may determine the length of the piston stroke that is obtained for any adjustment of the abutment member, markings are provided on the stem 22 to be read at the forward face of the cap 12. The markings are so spaced that the movement of the abutment member resulting from one complete rotation of the cap 12 will be equal to the distance between adjacent markings. Formed on the cap 12 are markings 30 cooperating with a reference mark 31 on the member 10, as shown in Fig. 4, so that the operator may determine very closely the position of the abutment member 20. It will be appreciated that the visible marking on the pin 22 nearest to the cap 12 plus the marking on the cap 12 opposite the reference mark 31 will

give the length of the piston stroke permitted by the abutment member.

After the abutment member has been moved to the desired position, it may be locked in place by rotating the pin 22 about its own axis to effect a clamping of the abutment portions 24 and 26 on the threads of the member 10. It will be seen that the shoulder formed on the pin 22 by the reduced portion 23 engages the forward face of the abutment member, and the portion 23 threaded only into the opening 25 tends to move the abutment portion 26 toward the portion 24 when the pin is rotated in a clamping direction. Formed in the outer end of the pin is a groove 32 for receiving an instrument, such as a screw driver, to rotate the pin in the desired direction. It will be appreciated that only a very slight rotation of the pin will be needed to obtain a clamping or releasing of the threads.

The piston 4 is shown herein carrying a chuck 34 adapted to support a tool, not shown, such as a drill. The chuck is fixed to a spindle 35 which extends axially through the piston and is rotatably supported by bearings, one of which is shown at 36. Shoulders 37 on the spindle engage the bearing races for holding it against longitudinal movement relative to the piston. The rear portion of the spindle 35 has a splined connection, as shown at 38, to the power shaft 39 of a motor 40 mounted upon a rear cylinder head 41. A piston portion 42 extends rearwardly from the piston portion 4 and is slidably received within a bore 43 formed in the rear cylinder head. The piston portion 42 is suitably bored to receive the power shaft 39 as the piston is moved rearwardly in the cylinder. Arranged on the piston portions 4, 9 and 42 are packing rings 44, 44' and 44'' sealingly engaging the walls of their respective cylinder bores.

For effecting reciprocation of the piston, there are provided passage means 45 and 46 communicating with opposite ends of the cylinder bore 3. Suitable valve means, not shown, may be provided for connecting the passage means 45 and 46 selectively to pressure fluid supply and exhaust.

To perform a drilling operation, the abutment member 20 is first adjusted by rotating the cap 12 manually until the markings on the pin 22 and the cap indicate that the desired forward movement of the motor piston will be obtained. The pin 22 is then rotated to clamp the threads of the abutment portions on the threads of the member 10 and effect a locking of the abutment member in place. The opposite sides of the piston portion 4 are then connected to pressure fluid supply and exhaust in a manner to effect reciprocation of the piston while the motor 40 is operated to rotate the spindle 35.

While there is disclosed in this application one form which my invention may assume in practice, it will be understood that it may be modified and embodied in various other forms without departing from the spirit or the scope of the appended claims.

What I claim as new, and desire to secure by Letters Patent of the United States, is:

1. An adjustable abutment for a piston reciprocating in a cylinder comprising, in combination, a cylindrical body fixed to one end of said cylinder and having a bore for receiving an end portion of said piston, an abutment member received within said bore for engagement by said piston to limit its travel in one direction, said abutment member having threaded engagement

5 with the walls of said bore, and means for adjusting the position of said abutment member including a member mounted for rotation relative to said cylindrical body about an axis coinciding with the axis of said bore and means interconnecting said abutment member and said rotatably mounted member for rotation together comprising a pin connected to one of said members and extending through an opening in the other of said members.

2. An adjustable abutment for a piston reciprocating in a cylinder comprising, in combination, an annular member fixed to one end of the cylinder and adapted to receive an end portion of said piston, an abutment member for said piston received within said annular member and having threaded engagement with the walls of the latter, a cap rotatably mounted upon said annular member, and rotary motion transmitting means interconnecting said cap and said abutment member and adapted to permit relative axial movement therebetween whereby said abutment member is caused to rotate in response to rotation of said cap and move axially with respect to said cylinder to vary the relative axial relationship between said cylinder and said abutment member.

3. An adjustable abutment for a piston reciprocating in a cylinder comprising, in combination, an annular member fixed to one end of said cylinder and adapted to receive an end portion of said piston, an abutment member received within said annular member and engageable by said piston, said abutment member having threaded engagement with the walls of said annular member, a cap rotatably mounted upon said annular member, means for holding said cap against movement longitudinally of said annular member, and a pin fixed to said abutment member at a point spaced radially from the axis of said annular member and extending forwardly through an opening in said cap for connecting said abutment member and said cap for rotation together while permitting bodily movement of said abutment member relative to said cap.

4. The adjustable abutment of claim 3 in which markings are provided on said pin and cap for indicating the position of said abutment member.

5. The adjustable abutment of claim 3 in which a cut is made in said abutment member to form separate abutment portions, and said pin is provided with a reduced portion extending through an opening in one abutment portion and threaded into an opening in the other abutment portion whereby a rotation of said pin effects a clamping of the threads on said abutment member in engagement with the threads on said annular member for effecting a locking of said abutment member in place.

6. An adjustable abutment for a piston reciprocating in a cylinder and having a portion extending through one end of the cylinder for supporting a working tool comprising, in combination, a cylindrical member fixed to the forward end of said cylinder, an annular abutment member received within said cylindrical member surrounding the forward portion of said piston and engageable by an end surface of the latter, said abutment member having threaded engagement with said cylindrical member, a cap rotatably mounted upon said cylindrical member, means for holding said cap against movement longitudinally relative to said cylindrical member, a cut formed through a portion of said abutment member between its ends, and a pin engaging por-

tions of said abutment member at opposite sides of said cut and adapted for rotation to effect relative movement of the portions separated by the cut, said pin extending forwardly through an opening in said cap and connecting said abutment member and cap for rotation together.

7. An adjustable abutment for a piston reciprocating in a cylinder comprising, in combination, an annular member fixed to one end of the cylinder and adapted to receive an end portion of said piston, an abutment member received within said annular member for engagement by said piston to limit its travel in one direction, said abutment member having threaded engagement with the walls of said annular member, a cap rotatably mounted upon said annular member, means for holding said cap against movement longitudinally of said annular member, and means connecting said cap and said abutment member for rotation together while permitting bodily movement of said abutment member relative to said cap comprising a pin connected to said abutment member and extending through an opening in said cap at the forward end of said annular member.

8. An adjustable abutment for a piston reciprocating in a cylinder comprising, in combination, a cylindrical body fixed to one end of said cylinder and having a bore for receiving an end portion of said piston; an abutment member received within said bore for engagement by said piston to limit its travel in one direction, said abutment member having threaded engagement with the walls of said bore; means for adjusting the position of said abutment member including a member mounted for rotation relative to said cylindrical body about an axis coinciding with the axis of said bore and means interconnecting said abutment member and said rotatably mounted member for rotation together comprising a pin connected to one of said members and extending through an opening in the other of said members; and locking means operable to prevent relative movement between said abutment member and cylindrical body.

9. An adjustable abutment for a piston reciprocating in a cylinder comprising, in combination, an annular member fixed to one end of the cylinder and adapted to receive an end portion of said piston, an abutment member received within said annular member for engagement by said piston to limit its travel in one direction, said abutment member having threaded engagement with the walls of said annular member, a cap rotatably mounted upon said annular member, means for holding said cap against movement longitudinally of said annular member, and means interconnecting said cap and said abutment member

for rotation together including a pin operatively interconnecting said cap and said abutment member to transmit rotary motion from the former to the latter while permitting longitudinally relative movement therebetween.

10. In a hydro-pneumatic power feed assembly comprising a power feed cylinder having ring-like end closure heads each providing a tubular body having a through bore adapted to operatively receive a piston member designed for limited reciprocation and a piston member having an external piston adapted for sealed sliding engagement with the bore of said cylinder, and axial extension of reduced diameter extending from each of the end faces of said piston portion and adapted for sealed sliding engagement with the bores of the respective cylinder end closure heads, one of said axial extensions terminating in an extension portion of further reduced diameter; an adjustable reciprocation limiting mechanism comprising a tubular extension on the one of said closure heads receiving said one of said axial extensions and extending in axial, surrounding, radially spaced relation to said extension portion to provide an annular open ended space and being provided with internal threads; and an externally threaded abutment member threaded into said annular space to a predetermined set position whereby, upon reciprocation of said piston in one direction, the end face of one of said axial extensions will contact said abutment member to limit the movement of said piston member to the desired length of stroke.

11. The combination defined in claim 10, including a cap member rotatably mounted on said extension of said head portion, said cap member having an axial bore in its radial wall surrounding the external wall of said extension portion and being mechanically connected to said abutment member to transmit rotary motion from the former to the latter while permitting relative axial movement therebetween.
